UNITED STATES PATENT OFFICE.

HENRY H. DENNIS, OF CHICAGO, ILLINOIS.

DESIGN FOR A BOX FOR WASHING-MACHINES.

SPECIFICATION forming part of Design No. 20,538, dated March 3, 1891.

Application filed November 1, 1890. Serial No. 370,083. Term of patent 14 years.

To all whom it may concern:

Be it known that I, HENRY H. DENNIS, a citizen of the United States, residing at Chicago, in the county of Cook and State of Illinois, have invented a new and original Design for Starching and Washing Machines, of which the following is a specification.

The invention relates to a new and original design for a washing and starching machine box.

The leading feature of the design is the hexagonal form of the box, the hexagon being composed of three long and three short sides, which are alternately arranged.

In the drawings, Figure 1 is a perspective view of a washing-machine box, showing the design. Fig. 2 is a transverse sectional view.

In the drawings, A designates an elongated hexagonal box composed of wide and narrow sides B and C, which are alternately arranged and form a hexagon having alternate long and short sides.

D designates hexagonal end pieces, which have long and short edges arranged alternately.

The large and small panels are arranged on the face of one of the large sides and form raised surfaces.

What I claim is—

The design for a washing-machine box herein shown and described, the same having essentially an elongated hexagonal form with alternate long and short sides and consisting of the wide and narrow sides, the hexagonal end pieces having alternate long and short edges, and the large and small panels arranged on the face of one of the large sides and forming raised surfaces, as set forth.

In testimony that I claim the foregoing as my own I have hereto affixed my signature in presence of two witnesses.

HENRY H. DENNIS.
